United States Patent Office

Des. 193,592

Patented Sept. 11, 1962

193,592

PROJECTOR

Josef Bönisch, Dresden-Weisser Hirsch, Germany, assignor to VEB Kamera- und Kinowerke Dresden, Dresden, Germany

Filed Nov. 25, 1960, Ser. No. 62,981

Term of patent 14 years

(Cl. D61—1)

FIG. 1 is a front perspective view of a projector in closed position, showing my new design;

FIG. 2 is a front perspective view thereof in open position;

FIG. 3 is a rear perspective view thereof in closed position; and

FIG. 4 is a rear elevational view thereof in open position.

I claim:

The ornamental design for a projector, as shown.

References Cited in the file of this patent

UNITED STATES PATENTS

D. 166,981 Knowles _____ June 10, 1952

OTHER REFERENCES

Ritz Camera Centers Catalog, © 1959 National Photo Dealers Advertising Assn., page 9, Brownie 8—Model 10 Movie Projector.